US00D616396S

(12) **United States Design Patent**
Sato

(10) **Patent No.:** **US D616,396 S**
(45) **Date of Patent:** **** May 25, 2010**

(54) **PEDESTAL OF HEAT INSULATING
CYLINDER FOR MANUFACTURING
SEMICONDUCTOR WAFERS**

7,484,958 B2 * 2/2009 Kobayashi 432/258
7,501,370 B2 * 3/2009 Narendar et al. 501/88

* cited by examiner

(75) Inventor: **Izumi Sato**, Oshu (JP)

Primary Examiner—Selina Sikder
(74) *Attorney, Agent, or Firm*—Burr & Brown

(73) Assignee: **Tokyo Electron Limited**, Minato-Ku
(JP)

(57) **CLAIM**

(**) Term: **14 Years**

The ornamental design for a pedestal of heat insulating cylinder for manufacturing semiconductor wafers, as shown and described.

(21) Appl. No.: **29/342,858**

(22) Filed: **Sep. 2, 2009**

(30) **Foreign Application Priority Data**

Mar. 12, 2009 (JP) 2009-005525

(51) **LOC (9) Cl.** 13-03

DESCRIPTION

(52) **U.S. Cl.** **D13/182**

FIG. 1 is front perspective view of a pedestal of heat insulating cylinder for manufacturing semiconductor wafers illustrating my new design;

(58) **Field of Classification Search** D13/182;
206/454, 711; 118/728, 729; 211/41.18;
432/241, 253, 258; D6/407

FIG. 2 is a front view thereof;

See application file for complete search history.

FIG. 3 is a rear view thereof;

(56) **References Cited**

FIG. 4 is a right side view thereof;
